FORM BINDING MACHINE

Ilya Scheinker, New York, N. Y.

Application January 24, 1950, Serial No. 140,277

45 Claims. (Cl. 11—1)

1

This invention relates to form-binding machines useful for the mechanical aligning, straightening, stacking and fastening together sheets of paper and the like, wherein pre-selected single sheets roughly arranged into desired groups (such as booklet signatures, business form sets, lined tablets, etc.) may be brought into alignment with each other and bound together by the application of adhesives.

Particularly in that portion of the binding art devoted to the binding together sets alternately comprised of printed forms interleaved with carbon paper, many devices have been developed in which printing, perforating, punching and other operations required on the printed form have been accomplished on continuous web presses, and later interleaved on machines known as "Collators" to provide the carbon paper interleaving. In machines of this type, the various parts of the web are bound to each other by the application of a continuous strip of adhesive applied between each part by rotary applicators. Registration, or the accurate positioning of each sheet of such sets with each other sheet, is obtained by punching accurately spaced holes along the edges of the webs during the printing operation, and later using these holes as feeding means in the collating machines, to prevent slippage and mislocation of the sheets with respect to each other. These guide holes are trimmed off prior to the final cut-off of the web into single sets. The disadvantages of this method include the necessity of a large paper wastage, the requirement of relatively large quantities of any given specification, the high cost of the equipment, the limitation of the number of parts to a set of the "stations" or backstand capacity of the collators, and the difficulties encountered because of variable stretches and shrinkages of the paper stock after being punched, often causing the guide holes to become unequally spaced to prevent their proper functioning as registration feeding means—and other difficulties.

These difficulties, and particularly the high cost in time and material in the preparation of the various rolls or webs of material to be collated and bound, have caused the unending search by printers and binders over many recent years for a simple and easy means of binding such "sets" of forms prepared by ordinary "sheet" printing methods.

Several machines have been devised to aid the "sheet" method of collating and binding. One of these, of the "conveyor" type, provides "stations" or locations for individual hand feeding of sheets by operators to a conveyor belt requiring one

2

operator for every "part" or separate sheet of the set being made. The sheets are positioned by pin guides on the belt, and adhesive applicators apply adhesive to each sheet between the feeding stations. The great disadvantage of this method and machine is that the failure to feed by any operator, or the misplacement of any sheet, causes the entire operation to cease until the error is corrected.

10 Another type, known as "Spot-Gluers" consists of a table to which an operator hand-feeds individual sheets to which adhesive is applied to each sheet between the feeding operations by a series of fingers containing the adhesive. While this type of device is used for the binding of sets of two to five sheets "parts," the requirement of feeding each sheet separately makes the operation relatively slow and costly where a greater number of parts is required.

20 A fourth method of binding sets in very common use is known as Edge-Padding. Forms to be bound by this method are pre-collated to the desired "set," jogged to register, trimmed to size, stacked in a "gluing rack," hand-painted with adhesive, dried and later sliced into individual sets.

It will be seen from the foregoing description that the steps in all of the methods in common use for collecting and binding "Sets," "Signatures," "Pads" and the like, consist of means to gather such groups in desired rotation and register and causing their various parts to adhere to each other by the application of adhesives. In the "sheet" methods described, it has been necessary to locate the sheets in a position of registry or alignment, sheet by sheet, and to apply the adhesive as a subsequent operation. In some instances, such as edge-padding, several subsequent operations have been necessary.

30 40 It is an object of my invention to provide an improved and simplified form-binding machine structure which may be economically manufactured from comparatively inexpensive parts but which will be of sturdy construction and will be reliable and efficient in operation over long periods of time and will require little attention and adjustment.

Another object of my invention is to provide a machine into which may be fed a group of loose, 50 different, roughly-gathered sheets comprising a multisheet form or set, which will align, "inside-glue" and discharge a single bound set; and a related object is to make provision for said machine to press and wipe the adhering edges when necessary and to align the finished individual sets.

Another object of my invention is to provide a form-binding machine equipped with means to accurately align roughly-gathered sets of sheets, from two to fifty or more, and automatically to present and feed to an adhesive supplying mechanism the proper edge and surface of the sheets for automatic application of adhesive.

Another object of my invention is to provide a machine equipped with means of applying adhesive simultaneously to the leading edges and adjacent inner surfaces of all sheets of a set or the like which it is desired to bind.

Another object of my invention is to provide for the delivery of aligned and bound sets in finished aligned groups.

Another object of my invention is to provide for the automatic binding of predetermined numbers of sheets of different weights or characteristics (such as carbon paper and printed forms) interleaved as desired, the adhesive being inside the bound edges of the sheets.

Another object of my invention is to provide a form-binding machine of the foregoing type with means to grip and remove the bound form or group of sheets from the adhesive applying means; and a related object is to provide additional means to press and wipe the edges of the bound sheets to remove adhesive which may be clinging to them.

A still further object is to provide in a machine of the foregoing kind means to clean off regularly and automatically the pressing and wiping means.

Other objects and advantages will become apparent as the invention is described in connection with the accompanying drawings.

My invention lies in my discovery that when individual sheets such as for making up any desired "set" are caused to align themselves with each other by the vibrations or motion of the edges against a stop plate coated with adhesive, in the course of this aligning movement their desired edge and surface portions adjacent to the edge become coated with the adhesive. Furthermore it was discovered that in such cases where it is advisable for purposes of avoiding adherence between sets or groups or for other reasons to pre-coat the adhesive material and merely reactivate it by a solvent, heat or pressure in the manner above-described, the same result could be accomplished. The experiments with the above combination demonstrate that adhesives, or adhesive-activating agents applied as described, may be made to cause the various sheets in the set to adhere to each other and that the adherence will occur at an instant when the desired edge of each sheet is in exact alignment with the corresponding edge of each other sheet, this being the desired relation.

From the above it will be seen and from the following description and drawings it will become clear that my invention provides a means for the automatic and simultaneous application of the necessary adhesive, adhesive activator or solvent or the like, to all of the sheets to be bound during the aligning process, whether the number of sheets be two or many more, and whether the sheets be the same or different in quality or size.

In describing the invention for simplicity of expression I refer to "glue" and "gluing" but it will be understood that I include thereby other liquid adhesives, adhesive solvents and activators, whether or not heat and pressure are also required as in the case of some plastic substance.

Referring to the drawings, Fig. 1 is a side elevation view of a machine embodying the principles of my invention;

Fig. 2 is a fragmentary detailed perspective view looking at the back side of the glue plate assembly;

Fig. 3 is a fragmentary detail perspective view of the connection between the glue plate and its support at the right end of the plate as viewed in Fig. 2;

Fig. 4 is a fragmentary detailed perspective view similar to Fig. 3 but of the connection between the glue plate and its support at the left end;

Fig. 5 is a fragmentary detailed perspective view of one end of the take-off mechanism by which the glued unit is taken from the glue plate for presentation to the wiping mechanism;

Fig. 6 is an end elevation view of the upper portion of the glue plate assembly with the take-off mechanism before it;

Fig. 17 is a side elevation view similar to Fig. 16 but with the wiping jaws closed;

Fig. 18 is a detailed view of the wiping jaw mechanism showing the pair of jaws at the right of Fig. 15 when those jaws are closed;

Fig. 19 is a view similar to Fig. 17 but with the wiping jaws open, the mechanism appearing as if seen looking in the direction of the arrows along line 19—19 of Fig. 15;

Fig. 20 is an end elevation view looking into the discharge end of the invention illustrated in Fig. 1.

The invention as illustrated is supported by a suitable frame work comprised of angle irons but any other suitable frame work may be employed.

Generally speaking, the invention comprises several related mechanisms. First, there is a table or support upon which are placed the sheets which will comprise the individual unit or form and which are to be glued together at one edge. On this table the sheets to comprise the form are vibrated or moved rapidly to align them with one another and are presented to the mechanism

for applying glue or other adhesive, adhesive activator or solvent or the like.

The second portion of the invention therefore comprises the "gluing" mechanism or assembly. This comprises the applicator or glue plate 50 and associated parts which are supported from the vertical posts 30 and 34.

After the sheets comprising the form are caused to adhere at their edge portions they are grasped by the third portion of the machine comprising the take-off mechanism designated generally by the letter T. (See Figs. 1 and 13.) The take-off mechanism presents the form to the fourth portion of the machine comprising the wiping mechanism. The wiping mechanism is designated generally by the letter W. (See Figs. 1, 13 and for details, Figs. 15 to 20.)

All of the foregoing generally-described portions of the invention are related functionally in the following way: The sheets comprising the form are caused to adhere by the gluing mechanism and then are taken by the take-off mechanism to be presented to the wiping mechanism which gently presses together the glued edges and wipes off the edge any adherent tiny globules of glue. Hence the machine does not complete its operations on the form until after the wiping mechanism has functioned. Following that the form is discharged.

With the foregoing in mind the details of the several portions of the machine will now be described.

The vibrating or jogging table 40 may be supported by means of S springs 42 from a stationary platform 41 located between and supported by the vertical posts 30, 31, 33 and 34. Structure of this sort is described and illustrated in my co-pending application S. N. 587,554, filed April 10, 1945, entitled "Jogging Machine." It will be understood, however, that the present invention is not limited to the use of such jogging or vibrating means as is illustrated and described in that application, such structure being mentioned merely as an example of a suitable sort of vibrating means. Any means which brings the edges into alignment by sliding movement of the sheets over one another can be used.

Upon the fixed platform 41 is mounted the driving motor 43 which through a pulley and belt drive operates the vibrating means designated generally by the numeral 40 in Fig. 11. (See also Fig. 1.) Upon the vibrating table 40 may conveniently be arranged a rail or guiding edge 45 so that as the sheets of paper which are to comprise the individual form are tossed upon the table 40, one edge of such sheets will work its way over with abutment against and be guided by the rail 45. The table 40 is preferably tilted at a convenient angle so as to cause the vibrating sheets to move toward the left-hand edge of the table as viewed in Fig. 1. As the sheets are caused to move in this manner by the vibration of the table, the forward edge of the sheets (the left edge in Fig. 1) will abut a glueplate 50 which is located and moves adjacent the forward edge of the jogging table 40. In this manner the sheets are lined up and ready for the application of the adhesive, adhesive activator or solvent or the like to their forward edges in the manner now to be described.

The gluing assembly

Referring to the form of the invention illustrated in Figs. 1, 2, 3, 4 and 6, a glue plate, preferably of metal, is mounted in such a way as to be

moved in a plane perpendicular to the jogging table 40 adjacent the table's forward edge. The glueplate 50 is pivotally supported on upwardly-extending rods 51 and 52 which are slidably mounted in guide blocks or bearings 53 and 54 (Fig. 6), mounted upon the vertical posts 30 and 34. The glue plate is caused to rise and fall by substantially vertical movement of the rods 51, 52. For this purpose on the top end of the right rod 51 (Fig. 2) a rectangular block 55 is secured. From the side of this block nearest the glue plate 50 there extends in a radial direction a headed pin 56. To receive the headed pin 56 there is mounted fixedly upon the glue plate 50 adjacent the right end thereof a block 57 having an inverted U-shaped recess opening into the bottom thereof, the recess being undercut for the head of the pin 56. By the described connection the glue plate is mounted at its right end pivotally and removably upon the rod 51.

At the left end the glue plate is mounted upon the rod 52 by a different pivotal connection. A block 58 is secured upon the rod 52 near its upper end and has a radial recess to receive a pin 59 laterally extending from a short link 60 which is secured to a block 61 fixedly mounted upon the left end of the glue plate 50. In order to guide the upper end of the rod 52 a fibre roller 63 is mounted axially upon the top rod. The roller may roll over the surface of a block 64 secured to the upper end of the glue plate 50. It is desirable that the roller be provided because of relative motion between the plate and the rod 52 as will now appear from the following description of the mechanism for raising and lowering the glue plate.

On the mid-portion of the rod 51 there is adjustably secured another block 66 to the inner side of which the upper end of a link 67 is pivotally connected. The lower end of the link 67 has a pivotal connection with a crank 68 mounted upon a horizontal shaft 69. The shaft 69 is driven by a motor 70 (see Figs. 1 and 7) mounted upon a horizontal frame bar between the vertical frame posts 30 and 31. A belt 71 connects a pulley on the drive shaft of the motor 70 with another pulley of a reduction gear box 72. A drive gear 73 on the opposite side of a box from the pulley meshes with a similar spur gear 74 mounted upon the shaft 69. In this manner the shaft 60 and the crank 68 are rotated.

In a similar manner at the opposite end of the shaft 69 there is mounted a crank 75 having a pin connection at its end with the lower end of a link bar 76. The upper end of the link bar 76 is connected pivotally with a block 77 adjustably mounted upon the mid-portion of the rod 52.

The crank arm 75 is longer than the crank arm 68 with the result that when the shaft 69 rotates the left end (referring to Fig. 2) of the glue plate moves higher or has a longer path than the right-hand. By reason of the unequal movement of the ends of the glue plate, the bottom of the plate lies in a horizontal plane when the plate is at its lowest point; and when it is at its lowest point the slot 82 is in register with the forward edges of the jogging table 40. When the plate is at its lowest point the bottom edge of the glue plate is within a trough 80 containing liquid adhesive or adhesive activator or the like and supported upon a horizontal frame member 81 connected between the vertical frame posts 30 and 34. The lower edge of the glue plate which lies within the trough is preferably serrated so that the liquid adhering thereto will drop off at the points of

the serrations rather than running down toward the lower end of the blade as the blade tilts as it rises.

From the foregoing it may now be seen that as the immersed lower edge of the glue blade 50 rises, it will rub over the forward edges of the sheets comprising the individual form F which are to be glued. The glue plate tilts as it rises because of the unequal movement of the ends of the plate as above described. When the glue plate is in its highest position, its lower edge is parallel with the edge of the jogging table. The vibrating action of the table causes the sheets of the form to move within a small compass over the wet face of the glue blade causing a very small amount of liquid or glue to enter between the sheets of the form at the forward edge. The very thin strip of glue or liquid which enters between the sheets is nevertheless sufficient to cause the sheets to adhere together at and adjacent their edges. The sheets at the moment of adherence are in register and thereafter remain so.

In order to remove or discharge the glued form, I provide in the glue plate a slot 82. This slot is at such an angle to the horizontal that the lower edge of the slot is in alignment with the edge of the vibrating table 40 when or at approximately the time that the glue blade is at its lowest point. Thus, the form F may move through the slot 82 under the force of gravity after being glued. It may then be collected in a container or removed by hand but I prefer to remove it mechanically and present the glued edge to wiping means as will presently be described. With some glues and under some circumstances it may possibly be unnecessary to wipe off the glued edge since ordinarily only a minute and very small number of droplets of glue will occasionally adhere to the glued edge of the form; but for most purposes it is essential that every trace of glue be removed.

From the foregoing it will be apparent that the unequal or tilting movement of the rising blade is necessary practically because of the tilted condition of the vibrating table 40 when considered against the necessity for having the glue trough in a horizontal position. Since for practical purposes it is desirable only to have perhaps about an inch of the lower end of the glue blade immersed in the glue trough, elevation of the blade without tilting is impractical if not inoperative because that would result in part of the edge of the form not being glued.

In Figs. 8-12 I have shown another form of gluing mechanism. Here the jogging table and jogging mechanism and the mechanism for raising and lowering the glue plate are as before. However, the glue plate differs from the previously-described form in that a larger slot or opening is provided, the purpose of which will be explained.

Instead of the forward edge of the form abutting the glue plate during the jogging and alignment of the sheets comprising the form F, a gate or bar 85 is provided closely adjacent the forward edge of the jogging table to hold the form upon the table during its alignment. The gate 85 is held slidably on extensions 30x and 34x of the posts 30, 34 by bolts 86 and 87 extending laterally therefrom and passing through parallel short slots 88 adjacent the opposite ends of the gate 85. To fractionally hold the gate 85 in whatever position it is moved into, springs 89 are coiled about the shanks of the bolts and press the bar against the surface of the extension 30x and 34x.

In the lower position of the gate 85 (wherein the top of the slots rest upon the bolts) the lower

edge of the gate is adjacent but below the forward edge of the jogging table so that the gate holds the forms thereon. In the upper raised position of the gate 85 wherein the lower end of the slots is next to the shanks of the bolts 86, there is a free space between the bottom edge of the gate 85 and the top of the jogging table 40. Hence it is possible for the form to slide under the gate.

Since the elevation of the gate 85 leaves a gap between the surface of the glue plate and the forward edges of the jogging table into which the form might slip, I provided a U-bent wire 90 or equivalent means, depending from the lower edge of the gate 85 and having its mid-portion parallel to and in alignment with the edge of the jogging table when the gate 85 is elevated. Thus this wire will fill the gap between the surface of the glue plate and the jogging table and enable the form F to move into the opening 93 in the glue plate 50 at the proper time and in the desired manner.

In order to elevate the gate at the proper time, I provide a pin 91 on the lower portion of the glue plate and extending laterally so as to engage the bottom surface of the gate 85. This pin is so located that it will elevate the gate at or immediately prior to the time the glue-covered zone across the bottom edge of the glue plate comes into alignment with the top of the jogging table. Thus as the gate is elevated the forward edges of the sheets of the form move over into engagement with that portion of the glue plate bearing the glue and the gluing takes place in the same manner as in the previously-described form.

As the operating mechanism for the glue plate continues, it starts to move the glue plate downwardly; but the gate remains elevated because of the friction-holding means (Fig. 10) previously described. While the glue plate is descending the large opening 93 provides the needed time interval for the form F to move through the glue plate and to be discharged or taken away by the take-off mechanism.

The glued form having been removed, it is now necessary to lower the gate into its starting or original position. For this purpose I provide a pin 92 near the top edge of the glue plate in position to engage the top edge of the gate 85 as the glue plate descends. Thus the gate is lowered into position for the sheets of the next form to be placed upon the jogging table and the operation completed.

The take-off mechanism

In order to take away the glued form F as it passes through the slot 82 in the glue blade 50 and to present the glued edge to wiping means, I provide mechanism including gripping jaws to grasp the form just back of the glued edge so that the glued edge is free and can be presented to wiping means as will now be described. As the edge of the glued form passes through the slot 82, it is gripped between a pair of relatively movable jaws 100 and 110 extending transversely from side to side of the machine. The lower jaw 100 comprises a rod, either round or flat-topped, which may be rubber-covered or not, with its ends fixedly mounted in oscillating parallel metal arms 102, 103 located on opposite sides of the machine. These arms are pivotally mounted at their bottom ends in such a way as to cause their oscillation in unison as will presently be described. The upper ends of the bars 102, 103 are bent as may be seen best in Fig. 6 to incline the

jaws so as to be at the same angle as the glue plate slot 82 and jogging table edge when the jaws are adjacent the slot and ready to grasp the edge of the form issuing therethrough.

The upper jaws 110 preferably comprise a square rod whose ends are slidably mounted within slots 105 in the upper ends of the oscillating arms 102, 103, the slots being just above the mounting of the lower jaw. In order to move the upper jaw 110 relative to the lower jaw, cast metal links 112 are connected with the ends of the upper jaw 110 which extends through the slot 105. To the lower ends of the links 112 are pivotally connected one end of crank arms 114 (as may best be seen in Fig. 5), the other end of the crank 114 being mounted rigidly upon a rock shaft 115 extending transversely of the machine below the jaw members and journaled rockably within the arms 102, 103. In order to rock the shaft 115, a rocker arm 116 is secured upon the rockshaft 115 extending radially therefrom having its free end connected pivotally to a longitudinally reciprocating connector bar 117 which extends downwardly and at its lower end has a slotted connection with a shaft 150. (See Fig. 13.) This reciprocating bar 117 is not caused to move by the shaft 150 but is simply guided thereby.

In order to move the connector bar 117 in the direction of its length, a roller 118 is provided extending from the side thereof near its lower end in position to engage with the upper surface of a rocking lever 119. The rocking lever is pivotally mounted upon a stationary stand 120 at one end and at its other end has a cam roller 122 adapted to follow a rotary cam 124 mounted upon a transverse cam shaft 125.

As the cam 124 rotates the rocking lever 119 rocks up and down and thus the connecting bar 117 is caused to move lengthwise up and down. To assist gravity, a spring 121 may be anchored at its upper end to the connector bar 117 and at its lower end to one of the fixed bearing supports 122 for the shaft 150. By this mechanism the upper jaw 110 is caused to move toward and away from the lower jaw 100.

In order to stop at just the right place the sliding of the form F through the jaws 100, 119 after application of glue, and in order that when the jaws grip the form the gripping will take place at precisely the right point, I provide curved stop fingers 130 (see Figs. 5 and 12) of which two or more may be mounted on an oscillating shaft 131 pivotally mounted and extending between the arms 102, 103. The location of these fingers in position to stop the form F is illustrated in Fig. 12.

To move the fingers out of the way as the take-off mechanism swings left (Figs. 1 and 13), I provide (see Fig. 5) on an extension of one end of the shaft 131 a crank arm 132 which is rocked by a connecting link 133 attached pivotally at one of its ends to the crank. Near the other end of the link 133 the free end of an idling crank arm 134 is pivotally connected, the idling crank being pivotally mounted on a pin 135 projecting from a lateral boss 136 on the oscillating arm 102. Laterally projecting at the lower end of the link 133 is a cam roller 137 riding on the under side of a stationary cam track or cam bar 138 extending alongside of the machine from the top of the vertical post 132 to a point below the level of the glue reservoir (see Figs. 1, 5, 13 and 15). The cam bar is made non-concentric about the pivot of the take-off mechanism but instead

with the curve at its left end flattened (see Fig. 13) whereby the link 133 is moved substantially in the direction of its length, causing oscillating of the shaft 131 and movement of the fingers 130 from the operative position of Fig. 12 to the inactive position of Fig. 5, and vice versa on return movement.

As the take-off mechanism moves from the gluing mechanism toward the wiping mechanism, the angle of the paper relative to the horizontal changes. At the start, the angle is substantially the same as that of the jogging table, ordinarily about 30°; at the wiping mechanism the angle is about 60°.

15 In order to support the form as it moves from the gluing mechanism to the wiping mechanism there are provided a series of spaced parallel thin supporting rods, 140, extending lengthwise of the machine from a transversely located shaft 141 pivotally mounted in bracket 144 on the wiping mechanism frame. At each end of the shaft 141 there is mounted a crank arm 142 urged in a counter-clockwise direction by a coiled tension spring 143 anchored to the frame of the wiping mechanism. The effort of the spring 143 exerted through the crank arm 142 upon the shaft 141 tends to move the supporting rods 140 in a counter-clockwise direction. This tendency is resisted by the rods coming into engagement with 30 the underside of the lower jaw member 100 of the take-off mechanism. As the take-off mechanism moves from the gluing mechanism toward the wiping mechanism, the rods 140 are thus urged to move in a counter-clockwise direction 35 from the position substantially as illustrated in full lines in Fig. 13 to the dotted line position. The form F is thus held at a sharp angle while being acted upon (see Fig. 13) by the wiping mechanism as will hereinafter be described.

40 When the wiping mechanism has completed its work, the form can thus be allowed to move under the force of gravity into a collecting basket or the like or it can be removed by mechanical means or manually as desired.

45 The gearing for the cam shaft 125 and the take-off mechanism is located upon a base plate B mounted at the bottom of the frame of the machine. The base plate is tilted from front to rear at about the same angle as the forward edge of the jogging plate. The part of the plate farthest from the observer in Fig. 1 is higher than the part nearest the observer.

The cam shaft 125 is mounted in fixed journals or bearings 125a and 125b supported on the 55 base plate B. The cam shaft 125 is driven by a bevel gear 145 mounted on the middle thereof and meshing with a similar bevel gear 146 mounted upon one end of a longitudinally positioned drive shaft 147 at right angles to the shaft 125. On the other end of the shaft 147 is a bevel gear 148 meshing with a like bevel gear 149 which is mounted upon the shaft 69 which as hereinbefore described is driven from the gear box 72.

65 For the purpose of causing the oscillating movement of the take-off mechanism T, a large disc cam 151 is fixedly mounted upon the shaft 125. A cam roller or follower 152 rides upon the periphery of the cam 151 and extends laterally from the end portion of a cam follower arm 153 which is mounted upon and oscillates with the shaft 150. Since the take-off mechanism arms, 102, 103, are fixedly mounted on the shaft 150, therefore that shaft operates the arms 10 and also loosely supports (Fig. 13) the connecting bar

117 which operates the jaws of the take-off mechanism. For the purpose of holding the cam roller 152 against the periphery of its cam 151, a tension spring 155 is connected with the cam arm 153 and is anchored to the frame of the machine.

As will hereinafter be more fully described, the wiping mechanism is driven from the driving means mounted upon the base plate B through the agency of a shaft 157 in alignment with the shaft 147, there being a bevel gear 158 upon the end of the shaft 157 meshing with the bevel gear 145. Upon the opposite end of the shaft 157 is a sprocket wheel connected by a chain 158 with a sprocket 159 on a common shaft 159s with a spur gear 190, to drive the wiping mechanism as will more fully appear. The shaft 157 is journalled in bearings 157a mounted upon the base plate B.

The wiping mechanism

Mounted on top of the frame posts 32, 35 are end supporting brackets of substantially triangular shape, 160, 161. Running transversely across the machine and supported in these brackets 160, 161 are parallel rods 163 and 164. The rod 163 is at a higher elevation and spaced lengthwise of the machine from the rod 164. Slidably mounted upon the rods 163, 164 are similar carriages designated generally by the numerals 165, 185, since these carriages are alike except that the wiper elements which they carry face oppositely. Hence only one will need to be described. These carriages comprise a bottom plate 166 upon which are molded bosses 167 which are bored to receive the rods 163, 164, but one boss may have an open side, if desired, to facilitate assembly. A top plate 168 is secured to the carriage by screws 169 entering into the body of the bosses so that the top plate 168 is spaced from the bottom plate 166. Extending from the back side of the carriages 165, 185 are bolts 165b and 185b (see Fig. 20) for engagement by operating levers as will now be described.

In order to drive the sliding carriages 165, 185, as heretofore indicated, the chain 158 engages with a sprocket wheel 159 rotatably mounted upon a transverse upwardly-inclined supporting bar 191 extending between the supporting frame posts 32 and 35. The large spur gear 190, driven by sprocket wheel 159, meshes with a like large spur gear 192 on a shaft 192s also mounted in the cross bar 191. Extending laterally from the face of the spur gears 190, 192 at a point near their peripheries are two bolts 193, the shanks of which extend through and slide within slots 194 of actuating bar or lever members 195, 196 pivoted at their lower ends upon spaced pins 197, 198 respectively, mounted in a lower cross bar 199 between frame posts 32, 35. At their upper ends the actuating bars 195, 196 have slots through which pass the pins 165b and 185b respectively. It will thus be seen that as the spur gears 190, 192 are caused to rotate in opposite directions, the actuating bars 195, 196 will move toward and away from each other causing the carriages 165, 185 to slide along the guide bars 163, 164 toward and away from each other.

The sliding carriages 165, 185 are inclined due to the location of the guide bars 163, 164, so that the carriages face upwardly at an angle, as illustrated in Fig. 17. Mounted in the upper face or top plate of the carriages is a pivot pin such as 210 which is screwed therein and has a smooth shank beneath a hexagonal head upon which shank are pivotally mounted, one on top of the

other, a pair of similar wiper-supporting members 212, 214. As illustrated in Fig. 18 the member 212 is on top and the member 214 is beneath it. The shape of the wiper members may be seen best in Fig. 18 and may generally be described as comprising a substantially circular body portion from which projects, in a radial direction, an enlargement or arm 212a, the similar arm 214a of the member 214 extending in a diametrically opposite direction. Laterally extending downwardly from the arms 212a and 214a are small abutment pins 212p and 214p in position to engage wiper-closing actuator bar members 222, 224 which are fixedly mounted upon brackets 220, 221 which in turn are mounted on the guide rods 163 and 164. The closing bars 222, 224 are so placed as to cause clockwise and counter-clockwise rotation of the wiper carriers 214, 212 respectively (into the position of Fig. 18) when the pins 214p, 212p engage the ends of closing bars.

Mounted upon an enlargement extending approximately at right angles to the arms 212a, 214a are the wiper elements 213, 215 which are preferably small metal blocks set into the carriers 212, 214, at right angles thereto and having either rubber or hard tips thereon. Reversely bent arms 212x, 214x extend from the enlargements 212, 214 and are connected by a tension spring 216 which is adapted to move across the axis of the pivot 210 as the members 212, 214 are rotated between closed position (Fig. 18) and open position (Fig. 15). Thus rotational movement is assisted by the spring 216 as the line of action of the spring crosses over the axis of the pivot pin 210; and holds the two members 212, 214 with their wipers 213, 215 either closed (in engagement with opposite sides of the form F, Fig. 18) or open (as in Fig. 15).

40 The rotational movements of the wiper carriers in the carriage 185 is in the opposite direction to that of the elements in the carriage 165 but the movement of the wiper elements 223, 225 together to grip the form F is the same in both carriages.

45 As the carriages 165, 185 move away from each other, they approach wiper-opening bar members 232, 234 and 232', 234' mounted upon brackets 236, 236' of any suitable form which are adjustably positioned at the desired places toward the opposite ends of the guide bars 163, 164.

The form is held stationary between the jaw members 100, 110 of the take-off mechanism during movement of the wipers toward the sides of the machine. Hence the wipers perform a wiping action over the entire forward or glued edge of the form, the one pair of wipers 213, 215 wiping from about the middle to the left edge and the other pair of wipers 223, 225 wiping from the middle to the left. The slight pressure exerted by the wiper elements upon the edge of the form as they are wiping across it, tends to improve the adhesion of the several sheets of the form while at the same time wiping off minute globules of glue which may be present on the edge.

From the foregoing it may be understood that as the carriages move toward the sides of the machine, the pins, for example, 212p, 214p of the wiper carriers 212, 214 will engage with the ends 70 of the opening bars 232, 234 and will thereby be caused to rotate in the opposite direction from that which they were rotated by the stops 222, 224. Thus the wipers will be caused to disengage the form F. This occurs after the wipers have 75 moved beyond the side edges of the form F dur-

ing their travel so that the form is therefore entirely free, for removal from the machine.

Since there may be a tendency for the glue to accumulate upon the wiper elements 213, 215, 223, 225, I provide between the pairs of opening bars 232, 234 and 232', 234', wiper-cleaning members mounted upon brackets 236, 236'. The cleaning members may be twisted metal bars 240 with sponge rubber tips 241. This wiper cleaner is so positioned that the tips 241 will tend to separate the wiper members 213, 215 or 223, 225 as they come into contact with said tips, thus starting the opening movement of the wiper elements which is continued by the engagement of the opening bars 232, 234, for example, with the pins 212p, 214p. Since the opening movement of the wiper carriers is accompanied by passage of the line of action of the spring 216 across the axis of the pivot 210, wiper carriers are held open (Fig. 15) by the action of the spring.

In order to make certain that there may not be a portion at the center of the glued edge which is not wiped, I provide for overlapping of the paths of the wipers at the middle of the edge of the form. I locate the fixed pivots 197, 198 of the actuating arms 195, 196 differently relatively to the pivots of the driving or spur gears 190, 192. By so locating these pivots one of these arms 195, 196 may be caused to move the carriage which it actuates further than the other. It makes no difference which of these carriages is moved further than the other as long as one carriage is carried a sufficient distance so that its wiper elements overlap the path of the wiper elements of the other carriage. By so relating the gears 190, 192 relatively to one another that the radii, on which the sliding pins 193 are located, do not ever align but so that one is slightly in advance of the other, it is possible to cause one set of the wipers to engage the glued edge of the form F and start its return movement just prior to the engagement of the other wipers with the form.

Operation

Assuming the gate 85 has just been lowered by the pin 92 on the glue plate, the glue plate will then have its bottom in the glue trough 80. At this time the loosely-gathered sheets of the form F are dropped on the table 40 and by reason of its jogging action are aligned against the guide rail and the gate 85. The cranks 68, 75 on shaft 69 which control the rise and fall of the glue plate being in the arc at the bottom of their rotation give an interval when there is no significant amount of vertical movement of the plate while the gate is down. During this interval and also while the plate rises until its pin 91 elevates the gate, the aligning of the sheets takes place.

When the gate rises the sheets move forward into edge contact with the glue plate and almost immediately (or simultaneously, if desired) their edges are rubbed with glue adhering to the bottom part of the blade.

The gate 85 remains up by reason of the frictional supports at its ends, illustrated in Fig. 10.

When the glue plate is descending and the gate is still up (before the pin 92 hits the gate), the opening 93 in the plate permits the passage therethrough of the glued sheets of the form. At this stage the take-off mechanism is adjacent the glue plate (see Fig. 12) ready to receive the glued form issuing through the opening 93. As the glued edge of the form F moves through the opening 93, it passes through the open jaws 100, 110 of the take-off mechanism and comes to rest against the stop fingers 130. Immediately there-

upon the upper jaw 110 moves down toward the lower jaw clamping the form adjacent its edge in the take-off mechanism by reason of the downward action of operating rod 117 through the action of cam 124 and cam rod 119 as illustrated in Figs. 1, 5, 13. Immediately thereafter the rotation of cam shaft 125 and its cam 151 causes rocking of the shaft 150 and arms 102, 103 thereon through the action of the cam follower 152 and its arm 153. (See Figs. 1 and 14.) The rocking of the arms 102, 103 is in a counterclockwise direction as the apparatus is viewed in Fig. 1, thus causing the take-off mechanism to move from the gluing mechanism over to the wiping mechanism W.

During this movement the cam roller 137 on link 133 of the take-off mechanism rolls upon the undersurface of the stationary cam roller 138 causing the link 133 and crank arm 132 to rock the shaft 131 (see Fig. 5) to move the stop fingers 130 out of the path of the form F.

Also during the aforesaid movement of the take-off mechanism the supporting bars 140 upon which the form F is held, rock in a counterclockwise direction from approximately the full line to the dotted line position of Fig. 13 by reason of the bias of spring 143 on the shaft 141 upon which those supporting rods are mounted. In this position the form is presented to the wiping mechanism.

When the form is presented to the wiping mechanism, the wipers 213, 215, 223, 225 are open as illustrated in Fig. 15. Assuming the carriage 185 is the first to reach the end of its inward travel under the action of the operating arm 196 driven by the gears 190, 192 (see Fig. 20) as the carriage 185 approaches the end of its inward travel, wiper-closing bars 122, 124 abut the right ends of the pins on the wiper carriers (corresponding to pins 212p and 214p, Fig. 18). This abutment causes rotation in a counter-clockwise direction of the wiper 223 which thereupon closes with a snap motion due to the action of the over-center spring 216. The wipers closed because of the action of that spring. At this stage the operating arm 196 starts to move the carriage 185 toward the outside of the machine again. This action causes the dragging or wiping of the wipers 223, 225 over one-half of the forward edge of the paper. As this wiping action continues to the edge of the paper, the wipers 223, 224 eventually come in contact with the cleaning element 241' which wipes off the glue.

At the time or immediately upon the carriage 185 starting its movement toward the outside of the machine, the wipers 213, 215 on the left hand carriage 165 close upon the glued edge of the paper. Their path of wiping over the left half of the glued edge overlaps to a slight degree the path of the right hand wipers 223, 225 so as to leave no intermediate unwiped area.

The wipers now being open, the form can be removed by hand or by automatic mechanism as desired, or can be allowed to drop into a basket or container by gravity as the form slides off the supporting rods 140 from the position illustrated in Fig. 13. While the take-off mechanism has been adjacent the wiping mechanism and during the operation of the wiping mechanism the gluing mechanism has been operating through its cycle as previously described. The rotation of the cam 151 will now cause the take-off mechanism to return to the position adjacent the gluing mechanism wherein it will be ready to repeat the operation just described. By the time the

take-off mechanism has returned to its position adjacent the gluing mechanism, the latter part of the gluing cycle will be in the process of completion so that as the glue plate descends and the glued form enters the opening 93 in the glue plate, the take-off mechanism is ready to enter upon its next cycle.

It is believed that the operation of the gluing mechanism illustrated in Figs. 1 to 6 will be clear from the description of the operation of the gluing mechanism of Figs. 8, 9 and 10. In the form of Figs. 1 to 6, the absence of the gate 85 does not affect fundamentally the essential function of the gluing. In the form of Figs. 1 to 6 the sheets of the form F are aligned and maintained in alignment by their abutment against the face of the glue blade and by the guide rail on the table until the time that the bottom part of the glue blade which carries the glue comes in contact with the forward edge of the form. From that point the gluing action is precisely as in the form of Figs. 8, 9 and 10. The functioning of the take-off mechanism is the same in each case.

From the foregoing it may be understood that the invention can be employed with sheets having a thin strip of dry glue or other inactive adhesive on an edge. The glue or adhesive may be activated by the glue blade dipping into a solvent or activator which by the mechanism described is thus introduced at the aligned edges of the sheets bearing the adhesive strip; with the result that adhesion may take place at the moment of exact alignment, as before.

If thermo-plastic or thermal setting adhesive is used, the heat or pressure or both can be applied by the take-off mechanism jaws, in which event they may be heated electrically from within by hot wire heating elements (not visible) or otherwise suitably connected by electric wires 180W, 110W at the ends of the jaws 100, 110 to a source of electric current.

In some cases the cutting of the sheets which are to make up the form may not have been accurate so that the edge of the papers may have a slight curvature. To take care of that condition I provide on the back of the gluing blade a tensioning arrangement comprising a bar 50a running across the mid-portion of the back of the blade. At each end it is screwed or bolted to the blade but spaced therefrom by washers. Fixedly mounted or welded on the plate near the mid-portion of the bar there are one or two spaced bolts 50b. The end of each screw passes through a bore in the bar. Through the bar transverse to each bore a slot is cut to receive a round thumb. Thus by turning the nut 50n so that it presses against one side or the other of the slot, the blade may be compelled to take a slight concave or convex bend so as to conform exactly with the edges of the sheets comprising the form.

It will be understood that the invention is not limited to the precise form and arrangement of parts herein illustrated and described. Since many modifications within the scope of my invention will occur to those skilled in the art, I do not limit the invention to the specific embodiments illustrated and described.

I claim:

1. In a machine, the means to apply adhesive to an edge and adjacent area of a sheet of paper or the like, comprising supporting means for the sheet, means positioned to be engaged by the edge of the sheet, means to apply a coating of

adhesive to said edge-engaged means, and means to cause a plurality of movements of said edge to and fro, over said adhesive-coated means.

2. In a machine, the means to apply adhesive to an edge and adjacent area of a sheet of paper or the like, comprising supporting means for the sheet, means positioned to be engaged by the edge of the sheet, means to apply a coating of adhesive to said edge-engaged means, and means to cause relative vibratory motion of said supporting means and edge-engaged means.

3. In a machine, the means to apply adhesive to an edge and adjacent area of a sheet of paper or the like, comprising supporting means for the sheet, means positioned to be engaged by the edge of the sheet, means to apply a coating of adhesive to said edge-engaged means, and means to vibrate said supporting means causing movement of said edge over said adhesive-coated means.

4. In a machine the means to cause inside adhesion of the edges of a plurality of sheets of paper or the like with said edges in alignment, comprising means to support said sheets, means to move said sheets slidably relative to one another, means positioned to be engaged by corresponding edges of said sheets and cooperating with said supporting means to produce an aligning action of said edges, and to apply liquid at said edges causing adhesion of said edges in exact alignment.

5. In a machine the means to cause inside adhesion of the edges of a plurality of sheets of paper or the like with said edges in alignment, comprising means to support the sheets, means cooperating with said supporting means to move the sheets slidably relative to one another to bring about alignment of an edge of each sheet with the corresponding edge of the other sheets, means positioned to be engaged by said edges of the sheets and to assist said aligning action and to apply liquid at said edges causing adhesion of said edges in exact alignment.

6. The machine as claimed in claim 5 wherein the supporting means is a table, and the means cooperating with the supporting means to move the sheets comprises vibrating means for jogging the table.

7. In a machine the means to cause inside adhesion of the edges of a plurality of sheets of paper or the like with said edges in alignment, comprising a vibrating table for said sheets having guide means thereon for one edge of said sheets, means adjacent one edge of said table to apply adhesive automatically to a second edge of said sheets while aligning them.

8. In combination, a vibrating table for aligning sheets of a form or the like, a plate adjacent an edge of the table, means to apply adhesive to a portion of said plate, means to move the plate substantially vertically while an edge of the sheets abuts the adhesive-covered portion of said plate to coat the inside edges of sheets of the form and cause them to adhere to each other in alignment.

9. In a machine the means to cause inside adhesion of the edges of a plurality of sheets of paper or the like with said edges in alignment, comprising means to align an edge of each sheet with corresponding edges of the other sheets, means to apply adhesive to said edges while the aligning means is operating, said aligning means cooperating with said adhesive applying means to cause adhesive to be applied entirely along the inside of one edge of said sheets only over

a thin strip directly adjacent the edge, whereby said sheets adhere in alignment.

10. In a machine the means to cause inside adhesion of the aligned edges of a plurality of sheets of paper or the like comprising a vibrating table on which said sheets may be aligned, and an adhesive-covered surface movable adjacent an edge of said table while the table is vibrating causing a thin strip of adhesive to enter inside an edge of said sheets and to secure said edges together in alignment.

11. A vibrating table, means cooperating therewith to cause alignment of sheets of paper or the like on the table, and means to apply adhesive automatically to an edge of the sheets and to cause adhesion at the moment of alignment, in combination with take-off mechanism for taking the adhering sheets from the adhesive-applying means and presenting them to wiping mechanism, wiping means rubbing over the adhering edges of said sheets while they are held by said take-off mechanism; and means to operate said wiping mechanism and said take-off mechanism in coordination.

12. Means including a vibrating table to align sheets of paper or the like and to automatically apply adhesive to aligned edges thereof, means to take off said sheets from said table and to present their adhering edges to wiping mechanism, wiping means rubbing over the said edges of said sheets while they are held by said take-off mechanism; and means to operate said wiping mechanism and said take-off mechanism in coordination.

13. A machine as claimed in claim 12 wherein the take-off mechanism comprises a pair of oscillating arms, relatively movable jaw members carried by said arms, means to close said jaws after the adhering edges of the sheets enter them, and to open said jaws after the wiping means has completed its operation.

14. A machine as claimed in claim 13 wherein the take-off mechanism includes means to locate the attached sheets between the jaws, and means to move said locating means out of the path of said sheets prior to their presentation to the wiping means.

15. A machine as claimed in claim 13 wherein the take-off mechanism includes means to locate the attached sheets between the jaws, and means to move said locating means out of the path of said sheets prior to their presentation to the wiping means, said means to move the locating means including a fixed cam track mounted on the machine and a cam follower carried by one of said oscillating arms.

16. A machine as claimed in claim 12 wherein the take-off mechanism comprises a pair of oscillating arms, relatively movable jaw members carried by said arms, one of said jaws being movably supported on said arms, cam operated means to move said jaw closed and open after the sheets have entered the jaws and after said wiping means have operated respectively.

17. A machine as claimed in claim 12 wherein the take-off mechanism comprises a pair of oscillating arms, relatively movable jaw members carried by said arms, means to close said jaws after the attached edges of the sheets enter them, and to open said jaws after the wiping means has completed its operation, said opening and closing means including a longitudinally movable member slidably mounted on the pivot of said oscillatable members, and cam means to move said longitudinally movable member.

18. A machine as claimed in claim 12 wherein the take-off mechanism comprises a pair of oscillating arms, relatively movable jaw members carried by said arms, means to close said jaws after the attached edges of the sheets enter them, and to open said jaws after the wiping means has completed its operation, and means to support the body of the paper during movement from the adhesive-applying means to the wiping means, said supporting means being tiltably supported on a shaft adjacent the wiping mechanism and spring-biased upwardly, the bias being permitted to act or overcome by movement of the take-off means toward or away from the wiping means respectively.

19. A machine as claimed in claim 12 wherein the take-off mechanism comprises a pair of oscillating arms, relatively movable jaw members carried by said arms, means to close said jaws after the attached edges of the sheets enter them, and to open said jaws after the wiping means has completed its operation and means to support the body of the paper during movement from the adhesive-applying means to the wiping means, said means to be tiltable upwardly responsive to movement of the take-off mechanism toward the wiping means whereby on opening of said jaws the attached sheets may exit by gravity from the machine.

20. In a machine means to align sheets of paper or the like, means to apply adhesive automatically to edges of the sheets while they are being aligned, means automatically to present the attached edges of the sheets to wiping mechanism, said wiping mechanism comprising pairs of wiping devices, and means to cause said devices to wipe opposite sides of said sheets at their attached edges.

21. A machine as claimed in claim 20 having means mounted thereon to clean off the wiping devices.

22. A machine as claimed in claim 20 having means tending to separate the wiping devices of each pair and at the same time to clean them.

23. In a machine means to align sheets of paper or the like, means to apply adhesive automatically to edges of the sheets while they are being aligned, means automatically to present the attached edges of the sheets to wiping mechanism, said wiping mechanism comprising pairs of wiping devices and means to cause one pair of said devices to wipe, in one direction, opposite sides of said sheets at their attached edges, and means to cause another pair to wipe in the opposite direction.

24. A machine as claimed in claim 23 wherein means are provided to cause the path of one pair of wiping devices to overlap the path of the other wiping devices.

25. A machine as claimed in claim 23 having slideable carriages, means to move said carriages between the mid-portion and the sides of the machine, said wiping devices comprising pivoted carrier means mounted on said carriages and having wiping means thereon, projecting means on said carrier means, and fixed closing means engageable by said projecting means to move said wiping devices into engagement with the sheets, fixed opening means also engageable by said projecting means to disengage said wiping devices from the sheets.

26. A machine as claimed in claim 25 having spring means connecting each pair of wiping devices to bias them open and closed.

27. A machine as claimed in claim 23 having

slidable carriages, means to move said carriages between the mid-portion and the sides of the machine, said wiping devices comprising pivoted carrier means mounted on said carriages and having wiping means thereon, means on said carriers to move said wiping means into and out of engagement with the sheets as the carriages reach the inner ends and the outer ends of their travel respectively.

28. A machine as claimed in claim 27 having means to hold each pair of wiping devices open and closed.

29. A machine as claimed in claim 20 having tensioning means to press said wiping devices against opposite sides of said attached edges while wiping the same.

30. In a machine means to cause interior adhesion of the edges of a plurality of sheets of paper or the like with said edges in alignment, comprising a tilted vibrating table for said sheets having guide means thereon for one edge of said sheets, means adjacent one edge of said table to apply adhesive to a second edge of said sheets while aligning them, a reservoir of adhesive into which said applying means dips, means to elevate said applying means more at one end than at the other so that the upper edge of the adhesive covering shall be substantially parallel to the aligned sheet edges on the table.

31. In a machine the means to cause interior adhesion of the aligned edges of a plurality of sheets of paper or the like comprising a tilted vibrating table on which said sheets are aligned, means to apply adhesive at aligned edges of said sheets while the table is vibrating to cause a thin strip of adhesive to enter inside an edge of said sheets and to secure said edges together at the moment of alignment, means to shield said sheets from contact with said adhesive-applying means while aligning them prior to applying adhesive, and means to elevate said shielding means when adhesive is to be applied.

32. In a machine, the means to cause interior adhesion of the aligned edges of a plurality of sheets of paper or the like comprising a tilted vibrating table on which said sheets are aligned, means to apply adhesive at aligned edges of said sheets while the table is vibrating to cause a thin strip of adhesive to enter inside an edge of said sheets and to secure said edges together in alignment, a reservoir into which said applying means dips, means to elevate said applying means more at one end than at the other so that the upper edge of the adhesive covering shall be substantially parallel to the aligned sheet edges on the table, means to shield said sheets from contact with said adhesive-applying means during alignment prior to applying adhesive, and means to elevate and lower said shielding means to expose the edges of the sheets when adhesive is to be applied.

33. In a machine, the means to cause interior adhesion of the aligned edges of a plurality of sheets of paper or the like comprising a tilted vibrating table on which said sheets may be aligned, means to apply adhesive at aligned edges of said sheets while the table is vibrating to cause a thin strip of adhesive to enter inside an edge of said sheets and to secure said edges together in alignment, a reservoir into which said applying means dips, means to elevate said applying means more at one end than at the other so that the upper edge of the adhesive covering shall be substantially parallel to the aligned

sheet edges on the table, means to shield said sheets from contact with said adhesive-applying means during alignment prior to applying adhesive, and means to elevate and lower said shielding means to expose the edges of the sheets when adhesive is to be applied, and means to hold said shielding means in elevated and in lowered positions when moved therein.

34. In a machine for causing interior adhesion of the edges of a plurality of sheets of paper or the like, a vibrating table, means associated therewith for aligning the sheets, means for applying adhesive to one edge of said aligned sheets while said sheets are vibrated by said table, means causing removal of the attached sheets from said table to a predetermined position, and wiping means acting on the attached edge of the sheets while in said predetermined position.

35. In a machine for causing interior adhesion of the edges of sheets of paper or the like, a vibrating table, means associated therewith for aligning the sheets, means adjacent one edge of the table and moving substantially perpendicularly to the plane of the table for rubbing over an edge of the sheets, means to apply a coating of an adhesive to said rubbing means for application to said sheet edges, means causing removal of the attached sheets from said table to a predetermined position, and wiping means acting on the attached edges of the sheets while in said predetermined position.

36. A machine as claimed in claim 34 wherein the wiping means comprises pairs of wiping devices pressing on opposite sides of the attached edges of the sheets and moving from the mid-portion of the edge outwardly.

37. A machine as claimed in claim 36 wherein the wiping devices simultaneously wipe so as to substantially equally pull on the attached edges in opposite directions.

38. A machine as claimed in claim 34 wherein the wiping means comprises pairs of wiping devices pressing on opposite sides of the attached edges of the sheets and moving from the mid-portion of the edge outwardly, and means to automatically engage said wiping devices with the sheets at the mid-portion of the attached edges, and means to automatically separate said devices upon conclusion of their wiping action.

39. A machine as claimed in claim 34 wherein the wiping means comprises pairs of wiping devices pressing on opposite sides of the attached edges of the sheets and moving from the mid-portion of the edge outwardly, and means to clean said wiping devices upon conclusion of each wiping operation.

40. In a machine the means to cause inside adhesion of the aligned edges of a plurality of sheets of paper or the like, comprising a vibrating table on which said sheets may be aligned, and an adhesive-covered surface movable adjacent an edge of said table while the table is vibrating causing a thin strip of adhesive to enter inside an edge of said sheets and to secure said edges together in alignment, and a flat clean surface adjacent the edge-to-be-secured in position tending to align said edges prior adherence.

41. In a machine the means to cause inside adhesion of the aligned edges of a plurality of sheets of paper or the like comprising a vibrating table on which said sheets may be aligned, and an adhesive-covered surface movable adjacent an edge of said table while the table is vibrating to cause a thin strip of adhesive to enter inside an edge of said sheets and to secure said edges to-

21

gether in alignment, and a flat clean surface adjacent the edge-to-be-secured in position for aligning said edges prior to adhesion, and means to raise and lower in unison said clean surface and said adhesive-covered surface.

42. In a machine the means to secure by interior adhesion the aligned edges of a plurality of sheets of paper or the like comprising a vibrating table on which said sheets may be aligned, and an adhesive-covered surface movable adjacent an edge of said table while the table is vibrating to cause a thin strip of adhesive to enter inside an edge of said sheets and to secure said edges together in alignment, and a flat clean surface adjacent the edge-to-be-secured in position for aligning said edges prior to adhesion, and means to elevate said clean surface and expose the edges of the paper to the adhesive-covered surface.

43. In a machine the means to cause inside adhesion of the aligned edges of a plurality of sheets of paper or the like comprising a vibrating table on which said sheets may be aligned, and an adhesive-covered surface movable adjacent an edge of said table while the table is vibrating to cause a thin strip of adhesive to enter inside an edge of said sheets and to secure said edges together in alignment, and a flat clean surface adjacent the edge-to-be-secured in position for aligning said edges prior to adhesion, and means to elevate and lower said adhesive-covered surface and said clean surface to expose the edges of the sheets to the adhesive-covered surface.

44. In a machine the means to cause inside adhesion of the aligned edges of a plurality of sheets of paper or the like comprising a vibrating table on which said sheets may be aligned, and an adhesive-covered surface movable adjacent an edge of said table while the table is vibrating to cause a thin strip of adhesive to enter inside an edge of said sheets and to secure said edges

22

together, and a flat clean surface adjacent the edge-to-be-secured in position for aligning said edges prior to adhesion, and means to raise and lower said adhesive-covered surface, means associated with said raising and lowering means operative to raise and lower said clean surface at predetermined points in the rise and fall of said adhesive-covered surface.

45. In a machine the means to cause interior adhesion of the aligned edges of a plurality of sheets of paper or the like comprising a vibrating table on which said sheets may be aligned, and an adhesive-covered surface movable adjacent an edge of said table while the table is vibrating to cause a thin strip of adhesive to enter inside an edge of said sheets and to secure said edges together in alignment, and a flat clean surface adjacent the edge-to-be-secured in position for aligning of said edges prior to adhesion, said clean surface being movable up and down, means to maintain said clean surface in elevated or lowered position, and means to raise and lower the adhesive-covered surface and to cause raising and lowering of the clean surface at predetermined points in the rise and fall of the adhesive-covered surface.

ILYA SCHEINKER.
